MEANS FOR ILLUMINATING SWITCH-HANDLES

Leon S. Brach, East Orange, N. J.

Application July 16, 1932, Serial No. 622,850

2 Claims. (Cl. 200—167)

This invention relates to electric switches and more particularly to means included within the switch mechanism itself for illuminating the handle thereof, whereby the same may be more readily located for operation, especially in the dark.

It is therefore the principal object of my invention to provide means integral with the switch mechanism for illuminating the switch handle whereby the same may be readily located.

Another object of my invention is to provide means as a part of the switch for illuminating the switch handle so as to indicate not only the location of the switch, but whether the switch is in "on" or "off" position.

Another object of my invention is to provide means comprising part of the switch for illuminating the handle, which means may be applied to various types of standard switches without changing the over-all dimension of the switches and adding but little to the cost thereof.

Another object of my invention is to provide illuminating means for a switch handle which can be connected across any of the usual low voltage circuits without change, and at the same time consume an extremely small amount of current.

These and other objects will be discerned from a reading of the specification taken in connection with the annexed drawing, wherein:

Figure 1 is a substantially full-size plan view of a well-known make of toggle switch, without the mounting plate, to which my invention has been applied.

Figure 2 is a view on the line 2—2 of Figure 1.

Figure 3 is a view on the line 3—3 of Figure 1.

Figure 4 is a view through the handle of the switch showing the illuminating means therewithin.

Figure 5 is an end-view of the central portion of the switch showing the toggle mechanism.

Figure 6 is a diagrammatic view of the circuit connections to the switch and the handle-illuminating device.

In the drawing, wherein like numbers refer to corresponding parts in the various views, 1 is a metal frame usually made of steel, having downwardly bent side-support members 2 and 3 between which is positioned a switch block 4, the same being carried on a pivot pin 5 insulated by the insulators 6 and 7 from the side members 2 and 3 for a purpose to be later referred to. The side members 2 and 3 carry a toggle frame member 8 on one side of which are supported a pair of switch members 9 and 10 which are insulated from the frame 8 by suitable insulators 11. The switch

block 4 carries a combined stop and spring-engaging member 12 having a fork 13 adapted to engage one end of toggle spring 14, the other end of which passes around a lug 15 on the frame 8, thus positioning the spring 14 within the toggle frame 8. The switch block 4 is also provided with an auxiliary stop member 16 for engaging the mounting plate 1 when the switch block 4 is in one position as shown in Figures 1, 2, and 4. When the switch block 4 is thrown to the opposite position, the lug 17 of the member 12 engages the mounting plate 1 to act as a stop.

The switch plate 1 is provided with tapped holes 18 and 19 for mounting the same on the hollow block or base member 20 made of some good insulating material such as porcelain. The base 20 carries a pair of contact members 21 and 22 to which circuit wires are adapted to be attached by means of screws 23 and 24. The contact member 21 is provided with a downwardly and inwardly extending lug 25, while the contact member 22 is provided with a lug 26. The lugs 25 and 26 are adapted to be engaged by the switch contact members 9 and 10 when the switch block 4 is moved to a position as indicated in Figures 1 and 2.

The previously described parts of the switch illustrated, except the special insulated pin 5, form no part of my invention but are merely to illustrate and describe more clearly the application of my invention thereto.

In order to illuminate the switch handle 27, I make the same hollow and preferably provide it with a screw-thread for screwing it into the switch block 4. The handle 27 is preferably made in its entirety of transparent or translucent material, although the stem part of the handle may be of opaque material, while the end 28 may be of transparent material to pass light therethrough, and in some cases, the end 28, whether separate or integral with the stem portion, may be provided with numbers so that any particular circuit may be readily identified.

The block 4 is provided with a socket 29 preferably of the screw-thread type, to receive a bulb 30 having a screw-base 31 to fit the socket 29. The lamp bulb 30 is provided with a pair of spaced electrodes 32 and 33, one of these electrodes being connected to the screw-base 31 of the lamp, while the other electrode is connected to the central electrode 34 of the bulb 30. The bulb 30 is evacuated and filled with neon gas. The pivot pin 5 carries a flexible contact 35 for engaging the central contact 34 of the lamp.

The socket 29 is attached by a suitable connection 36 to the frame 1 of the switch.

Mounted along one side 37 of the wall of the hollow base 20, is a resistance unit comprising an insulator 38, to one end of which is attached in any satisfactory manner, as by rivets or eyelets 39, a terminal strip 40. To the other end of the insulator 38 is similarly attached a terminal strip 41 which is adapted to be fastened to or held in contact with the switch lug 25. On one side of the insulator 38, is carried a resistor 42 preferably constructed in the same manner as grid-leak resistors used in radio circuits. When the switch is assembled, the end 43 of the pin 5 engages the end of the flexible terminal 40 of the resistor 42, thereby completing an electrical connection from the switch contact member 21 to the central point 34 of the lamp 30, and to one of the electrodes within the bulb 30.

By reference to Figure 6, it will be seen that one of the circuit wires 44 is connected to the terminal screw 23, while the other circuit wire 45 is connected to the frame 1 of the switch. When the switch is thrown so that the contacts 9 and 10 engage the contact lugs 25 and 26, a circuit is completed from the wires 44 and 45 through to the wires 46 and 47 leading outwardly from the switch. As shown by the full lines 48, the resistor 42 is connected to the terminal carrying the screw 24, and the opposite potentials of the circuit are applied to the lamp electrodes 32 and 33 when the switch members 9 and 10 are in circuit-closing position, and the bulb 30 will glow, indicating that the switch is in closed position and that a circuit is completed through the switch. If the wire 48 be connected to the screw terminal 23, as indicated by the dotted line 49, then the lamp 30 will glow all the time whether the switch be on or off, thereby indicating the location of the switch so that the operator can readily find it even in the dark.

The grid-leak resistor is very high and its purpose is to limit the amount of current consumed by the lamp, so that even if the lamp be connected by the lead 49 to the terminal screw 23 as above described, the amount of energy consumed is infinitesimal. In some cases or types of switches, it may be advisable to use two resistors, one in each lead running to the lamp electrodes 32 and 33, in order to reduce the chances of short circuit produced by flash-over in the resistor, if one of the grid-leak type is used; or in some cases, the resistor may be divided into two separate portions connected in series to one of the lamp electrodes.

If there is plenty of space available, a high-resistance wire type of resistor may be used instead of one of the grid-leak type.

While I have shown and described my invention as applied to one form of toggle switch, it is to be understood that this invention may be applied to other types of switches and it is also to be understood that the switch may be provided with a small auxiliary make and break contact arranged so as to open the circuit through the neon bulb when the switch is in closed position, so that the switch handle would be lighted only when the circuit is open.

From what has been said, it will be seen that the extra parts required to apply my invention to a standard type of switch, are very few and may

be readily applied at a very low cost and without increasing the space required for mounting the switch.

It will also be observed that the type of lamp used for illuminating the handle is of a character such that it can be made very small, considerably smaller than a filament type of lamp, for as has already been pointed out, the amount of current consumed is extremely small because of the type of lamp used, and the fact that the resistor used is preferably of the order of 50,000 ohms or even higher, and the lamp, provided the switch construction is satisfactory, can be connected across any of the low voltage circuits; namely, 110, 220, 440 volts, without change. It is also pointed out that one part of the handle circuit is grounded. Completion of the ground circuit can be readily made through either the conduit or pickup usually close to the switch since a good ground contact is not necessary because of the nature of the lamp as has been explained.

Another great advantage of my invention is that the handle is lighted with a softly glowing light which is highly desirable in many places where a switch of this character is adapted for use. It will be obvious that the details for carrying my invention into practice may be varied over a considerable range, and I therefore do not wish to be unduly limited in the interpretation of the scope of the appended claims.

Having thus described my invention, what I claim is:

1. Illuminating means for a switch-handle, including a hollow handle at least some portion of which will pass light rays, a metallic frame, a switching member pivotally mounted on said frame and having means to receive said handle, a bulb socket carried by said member and electrically connected to said frame, a flexible contact carried by the pivot pin, an inert, gas-filled bulb carried by said socket and having terminals adapted to engage said socket and flexible contact on the pivot pin, said bulb having a pair of spaced electrodes therein connected to the bulb terminals and capable of being connected without change directly across any low voltage circuit, said bulb extending into the hollow handle, and at least one high resistor arranged to be connected in series through said pin and flexible contact carried thereby with said electrodes when the same are energized.

2. In a switch having main circuit terminals, a metallic frame, a base carrying said frame, a switching member pivotally mounted in said frame by a metallic pin, a hollow handle attached to said switching member, a lamp-bulb socket carried by said switching member and having an electrical connection with the frame, a gas-filled bulb having a terminal to fit said socket, said bulb extending into the hollow handle, said handle being of a material which will pass light rays, an electrode within the bulb connected to said terminal, a second electrode within the bulb and connected to the central contact on the bulb, a flexible contact carried by the pivot pin and engaging said central bulb contact, at least one high resistor carried within the switch-base and having a flexible terminal to engage said pivot pin, said resistor having its other terminal connected to one of the main switch terminals.

LEON S. BRACH.
